COAT AND TROUSERS HANGER

George A. Higgins, Jr., Huntington, Ind.

Application February 4, 1942, Serial No. 429,537

8 Claims. (Cl. 223—91)

This invention is a novel improvement in coat and trousers hangers, and the principal object of the invention is to provide a hanger of simple construction which may be formed of relatively stiff wire, and may be utilized not only as a hanger for men's coats and trousers, but may also be used for hanging many other garments.

Another object of the invention is to provide a hanger of the above type including a pair of clamping bars carried by the hanger, said bars being supported by pairs of vertically disposed wires at each end rather than by a single pair of wires at the central or middle portion, whereby the bars will exert a double clamping effect upon the garment which is held therebetween, the pairs of wires at each end of the clamping bars being disposed in parallel relation and terminating at their upper ends in upwardly extending loops having narrow entrances to yieldably receive eyes slidably mounted on the pairs of vertical wires, which eyes are connected together by a single horizontally disposed actuating member, whereby when the actuating member is raised the eyes will yieldably enter the loops at the upper ends of the pairs of wires and hold the actuating member in such position permitting the clamping bars at the lower ends of the pairs of wires to be separated sufficiently to place a garment therebetween without having to manually hold the clamping member in raised position; said eyes of the clamping member being readily released from the loops when the clamping member is subsequently manually depressed to slide the eyes downwardly on the pairs of wires and thereby draw the lower ends of the pairs of wires and consequently the clamping bars together.

Further objects of the invention are to provide a hanger of the above type having an extension at its upper end beside the support engaging hook for holding a hat or the like; and to provide a hanger having a modified hook for supporting the hanger designed to eliminate catching of the outer end of the hook on garments or other hangers.

Other minor objects of the invention will be hereinafter set forth.

I will explain the invention with reference to the accompanying drawing, which illustrates several practical embodiments thereof, to enable others to adopt and use the same; and will summarize in the claims the novel features of construction for which protection is desired.

In said drawing:

Fig. 1 is a plan view of my novel coat and trousers hanger.

Fig. 2 is a side elevation thereof.

Fig. 3 is a horizontal section on the line 3—3,

Fig. 1.

Fig. 4 is a vertical section on the line 4—4,

Fig. 1.

Fig. 5 is a detail plan view of a modification.

As shown, my novel coat and trousers hanger is preferably formed of wire of suitable size and rigidity, said hanger being of substantially triangular shape and consisting of a pair of upwardly converging wires 1 and 2, forming the upper portions of the inclined sides of the triangular hanger, which wires 1 and 2 are twisted together as at 3 at the apex of the hanger to lock the same together. Wire 1 continues beyond the twisted portion 3 and is shaped to form a relatively large hook 4 adapted to be hung over a horizontal supporting rod or the like in the usual manner, the outer tip of the hook portion 4 being formed as a small loop 5 the outer end of which contacts the inner periphery of hook 4 to eliminate catching the hook 4 in garments or other hangers, and also to hold the hook 4 yieldably upon the supporting rod.

The wire 2 above the twisted portion 3 preferably continues in an upwardly inclined direction as at 6 to a point above the upper end of hook 4, and terminates in a loop 7 serving as a convenient hat support for the hanger. However, the members 6 and 7 may be omitted, if desired, and the wire 2 discontinued above twist 3.

As shown in Figs. 1 to 4 inclusive, a third wire 8 forms the base of the triangular hanger, wire 8 having upwardly bent portions 8a forming the lower corners of the triangle, the portions of the wire 8 beyond the bends 8a continuing upwardly and inwardly as at 8b at angles in substantial alignment with the wires 1 and 2 below twist 3, to the lower ends of which wires 1 and the portions 8b are joined, as hereinafter explained.

Upon wire 8, at the center of the hanger, is a fixed clamping bar 9 forming one of the clamps of the trousers hanger, said wire 8 preferably passing through a longitudinal bore in the clamp 9.

The meeting ends of the lower portions of wires 1 and 2, and the upper portions 8b of wire 8, are twisted together as at 10, said twisted portion extending substantially horizontally and inwardly of the hanger, the lower ends of wires 1 and 2 beyond the twists 10 being bent to form upwardly extending loops 11 having narrow entrances at the lower ends of the loops 11, said wires 1 and 2 beyond the loops 11 extending downwardly as at 12, and being anchored in clamping bar 9 to pre-

vent rotation or axial movement thereof on wire 8.

The portions 8b of wire 8, beyond the twists 10, are likewise bent to form upwardly extending loops 16 (Figs. 2 and 4) which are disposed directly opposite and adjacent their related loops 11, said loops 16 being of same size and shape as loops 11, the wires 8b beyond the loops 16 extending downwardly, as at 17, directly opposite and adjacent wires 12, said wires 17 having their lower ends anchored in a second clamping bar 18 disposed parallel with and adjacent the clamping bar 9, whereby the clamping bars 9 and 18 may be separated when the wire portions 12 and 17 are separated, and may be drawn together when the wires 12 and 17 are drawn together.

The loop portions 11 and 16 of the wires 1, 2 and 8 preferably have narrow entrances at their lower ends, the vertical portions of the loops passing closely adjacent the ends of the twisted portions 10, and vertically slidably mounted upon the pairs of wires 12 and 17 is a horizontally disposed actuating member 19 having eyes 20 at its ends embracing their respective pairs of vertical wires 12 and 17, said eyes 20 being of such diameter that when the member 19 is lowered the wires 12 and 17 will be drawn together and will draw the clamping bars 9 and 18 together, but when the member 19 is moved upwardly the clamping bars 9 and 18 may be separated to insert the garment therebetween.

An important feature of my invention is to provide means for maintaining the actuating member 19 in raised position preparatory to placing the garment between the clamps 9 and 18. According to the above construction the member 19 may be moved upwardly until the eyes 20 thereof pass through the narrow entrances of the yieldable loops 11 and 16, whereby the eyes 20 will maintain the member 19 in elevated position due to the positioning of the eyes 20 above the contracted lower ends of the loops 11 and 16, and thus it will not be necessary for the operator to utilize one hand to hold member 19 raised in position while positioning the garment between the clamping bars 9 and 18, which bars when the member 19 is raised may be separated to permit the garment to be inserted therebetween. As soon however as the garment has been so placed the member 19 may be lowered under a slight pressure to disengage the eyes 20 from their positions within the loops 11 and 16, and the member 19 depressed to a point adjacent the clamping bars 9 and 18, whereupon the eyes 20 will have drawn the clamping bars 9 and 18 into locking position to clamp the garment therebetween.

Instead of using a continuous base wire 8, as shown in Figs. 1 to 4 inclusive, wire sections 21 may be used, as indicated in Fig. 5, said sections 21 having their inner ends merely anchored in the ends of the fixed clamping bar 9. However, each wire section 21 is of such length that it may be formed into the shapes corresponding with portions 8a-8b-10-16 and 17 of wire 8 as shown in Figs. 1 to 4.

I do not limit my invention to the exact forms shown in the drawing, for obviously changes may be made therein within the scope of the claims.

I claim:

1. A hanger, comprising an open frame formed of relatively stiff wire or the like, and having a hook; the opposite sides of the frame being formed of upper and lower substantially aligned wire sections respectively overlapping at their adjacent ends, said overlapping portions of the

upper and lower wires at each side of the frame being secured together and bent to form opposed inwardly extending portions; said inwardly extending portions being bent to form opposed upwardly extending loops beyond the inwardly extending portions in which loops the pair of wires are parallel and are disposed closely adjacent; the respective loops having narrow entrances at their lower portions; the wires beyond the loops

extending downwardly to form pairs of vertical wire sections; a pair of clamping bars supported respectively adjacent their ends by the pairs of vertical wire sections; and a clamping member having eyes at its ends embracing the respective pairs of vertical wire sections; said eyes being adapted to enter the narrow entrances of the loops and to be yieldably confined within the opposed loops when the clamping member is raised.

2. In a hanger as set forth in claim 1, said narrow entrances being formed between the inner ends of the inwardly extending portions and the vertical wire sections.

3. A hanger comprising a substantially triangularly shaped open frame consisting of a pair of upwardly and inwardly converging wires forming the upper portions of the inclined sides of the frame, said wires being secured together at the apex of the frame; an integral hook above the apex; a third wire forming the base of the triangle and having opposed upwardly and inwardly bent portions forming the lower portions of the inclined sides of the frame; the upper and lower wire portions of the sides of the frame overlapping and being secured together to form a pair of inwardly extending wires at each side of the frame; the pairs of wires at each side of the frame being bent to form opposed upwardly extending loops beyond the inwardly extending portions in which the pair of wires of each loop are parallel and lie closely adjacent; the loops having narrow entrances at their lower portions; the pairs of wires at each side of the frame beyond the loops extending vertically downwardly to form a pair of vertical wire sections; a pair of clamping bars supported respectively adjacent their ends by the pairs of vertical wire sections; and a clamping member having eyes at its ends embracing the respective pairs of vertical wire sections; said eyes being adapted to enter the narrow entrances of the loops and to be yieldably confined within the opposed loops when the clamping member is raised.

4. In a hanger as set forth in claim 3, said narrow entrances being formed between the inner ends of the inwardly extending portions and the vertical wire sections.

5. In a hanger as set forth in claim 3, said third wire passing through a longitudinal bore in one of the clamping bars.

6. In a hanger as set forth in claim 3, said third wire being formed in two sections having its ends respectively anchored in the ends of one of the clamping bars.

7. A hanger comprising a substantially triangularly shaped open frame consisting of a pair of upwardly and inwardly converging wires forming the upper portions of the inclined sides of the frame, said wires being secured together at the apex of the frame; a hook extending from the apex; a third wire forming the base of the triangle and having opposed upwardly and inwardly bent portions forming the lower portions of the inclined sides of the frame; the upper and lower wire portions of the sides of the frame over-

lapping and being secured together to form a pair of inwardly extending wires at each side of the frame; the pairs of wires at each side of the frame being bent to form opposed upwardly extending loops beyond the inwardly extending portions in which the pairs of wires of each loop are parallel and lie closely adjacent; the loops having narrow entrances at their lower portions; the pairs of wires at each side of the frame beyond the loops extending vertically downwardly to form a pair of vertical wire sections; a pair of clamping bars supported respectively adjacent their ends by the pairs of vertical wire sections; a clamping member having eyes at its ends embracing the respective pairs of vertical wire sections; said eyes being adapted to enter the narrow entrances of the loops and to be yieldably confined within the opposed loops when the member is raised; said narrow entrances being formed between the inner ends of the inwardly extending portions and the vertical wire sections; and said third wire passing through a longitudinal bore in one of the clamping bars.

8. A hanger comprising a substantially triangularly shaped open frame consisting of a pair of upwardly and inwardly converging wires forming the upper portions of the inclined sides of the frame, said wires being secured together at the apex of the frame; a hook extending from the

apex; a third wire forming the base of the triangle and having opposed upwardly and inwardly bent portions forming the lower portions of the inclined sides of the frame; the upper and lower wire portions of the sides of the frame overlapping and being secured together to form a pair of inwardly extending wires at each side of the frame; the pairs of wires at each side of the frame being bent to form opposed upwardly extending loops beyond the inwardly extending portions in which the pairs of wires of each loop are parallel and lie closely adjacent; the loops having narrow entrances at their lower portions; the pairs of wires at each side of the frame beyond the loops extending vertically downwardly to form a pair of vertical wire sections; a pair of clamping bars supported respectively adjacent their ends by the pairs of vertical wire sections; a clamping member having eyes at its ends embracing the respective pairs of vertical wire sections; said eyes being adapted to enter the narrow entrances of the loops and to be yieldably confined within the opposed loops when the member is raised; said narrow entrances being formed between the inner ends of the inwardly extending portions and the vertical wire sections; and said third wire having its ends respectively anchored in the ends of one of the clamping bars.
